UNITED STATES PATENT OFFICE.

CHRISTIAN GOTTWALD, OF CLEVELAND, OHIO, ASSIGNOR TO THE RIC-WIL COMPANY, OF CLEVELAND, OHIO, A CORPORATION OF OHIO.

UNDERGROUND-CONDUIT CONSTRUCTION.

1,314,866.

Specification of Letters Patent.

Patented Sept. 2, 1919.

Application filed October 26, 1917. Serial No. 198,558.

To all whom it may concern:

Be it known that I, CHRISTIAN GOTTWALD, a citizen of the United States, residing at Cleveland, in the county of Cuyahoga and State of Ohio, have invented a certain new and useful Improvement in Underground-Conduit Construction, of which the following is a full, clear, and exact description.

10 This invention relates to the kind of underground conduits which are used to contain, protect, and prevent the loss of heat from pipes through which steam or other heated fluid is distributed.

15 The main object of the invention is to enable the use, for this purpose, of hollow tile segment blocks, substantially like those which are in common use in sewer construction. But to do this it has been necessary 20 to modify these hollow tile segment blocks in the manner and to the extent hereinafter set forth, and to associate the conduit formed with such modified segment blocks with a certain supporting base, and with means for 25 under draining, all as shown in the drawing and hereinafter described. And the invention consists in the resulting combinations of parts as pointed out in the appended claims.

30 In the drawing, Figure 1 is a vertical transverse section of an underground conduit construction in which the present invention is embodied; Fig. 2 is a vertical longitudinal section through the lower part 35 of said conduit construction.

Referring to the parts by reference characters, 10 represents a concrete base, having in its upper surface a longitudinally extended drainage groove 12. 15 represents 40 the conduit proper; and 25 represents the steam pipe therein.

The conduit 15 is built up of a plurality of segment blocks 16. Each of these segment blocks is formed with an inner row 45 of longitudinal holes 16^a through it, and with an outer row of longitudinal holes 16^b. These blocks are laid with mortar or cement joints between them, in the usual way, to 50 form a cylindrical conduit of any desired length. And all of these segment blocks except the segment block marked 17 are preferably made of vitrified tile. The segment blocks 17 are placed at frequent longitudinal intervals at the very bottom of the

conduit. These blocks are like the other 55 blocks except that they are made of cast iron; and each is formed with integral standards 17^a projecting inward from the inner surface of the block, said standards being for the purpose of supporting rollers 60 18 on which the steam pipes 25 rest, whereby said steam pipes may, as they expand and contract, be able to move freely longitudinally. Likewise these blocks 17 have a 65 drainage hole 17^b through them from the inner to the outer surface, which drainage holes are arranged to discharge into the drainage groove 12 in the base.

To prevent the escape of heat from this conduit the outer row of holes 16^b is 70 packed with insulating material 19. The inner holes 16^a need not be so packed, because the air imprisoned therein will act in a large degree as a heat insulator, provided that air is not allowed to circulate 75 freely, lengthwise of the conduit. To prevent this the holes 16^a are plugged at frequent intervals by plugs 20 which may be made from the mortar used to join the ends of the segment blocks. Preferably these 80 mortar plugs are put into both ends of the inner row of holes of each segment block. The air, therefore, within these holes, is prevented from circulating, and therefore 85 acts as an effective insulator since it can not carry away from a given block any heat which it absorbs.

In the formation of the conduit construction the base 10 is first laid or formed in the trench, with the drainage groove 12 in 90 its upper surface. Upon this base a thick but plastic layer 13 of cement is placed, and the segment blocks or the lower courses thereof are laid in this plastic layer, wherefore this layer will assume on its upper surface the external form of the conduit and therefore serve as an efficient support therefor.

In order to keep dry the earth which covers the described conduit, which is necessary 100 for the purpose of minimizing the loss of heat, a longitudinal row of drain tile 30 is laid in the trench on each side of the base 10, and these rows of drain tile are then buried in tightly packed porous material 105 such as crushed stone or gravel. This insures that the earth which covers the conduit shall be well drained and kept fairly

dry, and therefore in condition where it is capable of absorbing the minimum of heat from the conduit.

It is desirable also to form in the concrete base at intervals downwardly inclined drain holes through which water delivered into the drainage grooves 12, may be discharged into the mass of loose material at the side of the base in which the drain tile 30 is buried.

Having described my invention, I claim:

1. In underground conduit construction for steam pipes, a tubular conduit which is built of a plurality of segment blocks laid with mortared joints, each segment block having an outer and an inner row of longitudinal holes which two rows of holes are alined with corresponding rows of holes in adjacent blocks, insulating material packed in the outer row of holes, and plugs filling the inner row of holes at frequent longitudinal intervals.

2. In underground conduit construction for steam pipes, the combination of a base whose upper surface is concave and fitted to the conduit which it supports and which has a longitudinal drainage groove in its top surface, a cylindrical tubular conduit which rests upon said base and is built up of cellular segment blocks, of which certain blocks in the lowest course, located at longitudinal intervals, have holes through them discharging into said drainage groove in the top of said base, and the cells in said blocks being plugged at frequent longitudinal intervals to prevent the flow of air to said cells from one block to another for any considerable distance.

3. In underground conduit construction for steam pipes, a tubular conduit which is built up of a plurality of segment blocks laid with mortar joints each segment block having an outer and an inner row of longitudinal holes, insulating material packed in the outer row of holes, plugs filling the inner row of holes at frequent longitudinal intervals, said conduit having in its bottom course and at frequent longitudinal intervals

a segment block made of metal having a drainage hole which extends downward through it and having also integral standards projecting upward from its inner surface.

4. Underground conduit construction for steam pipes comprising in combination a concrete base having a longitudinal drainage groove in its upper surface, a tubular conduit which is supported upon said base and is built up of a plurality of segment blocks each of which has an outer and an inner row of longitudinal holes, insulating material packed in the outer row of holes, plugs filling the inner row of holes located at frequent intervals, said conduit having in its bottom course and at frequent longitudinal intervals a segment block made of metal having through it a drainage hole which communicates with the drainage groove in the base, and having integral standards projecting upward from its inner surface, and 70 rollers supported by said standards.

5. Underground conduit construction for steam pipes comprising in combination a concrete base having a longitudinal drainage groove in its upper surface, a tubular conduit which is supported upon said base and is built up of a plurality of segment blocks each of which has an outer and an inner row of longitudinal holes, insulating material packed in the outer row of holes, plugs in the inner row of holes located at frequent intervals, said conduit having in its bottom course and at frequent longitudinal intervals a segment block made of metal having a drainage hole which communicates with the 85 drainage groove in the base, and having integral standards projecting upward from its inner surface, rollers supported by said standards, a row of drain tile located below the conduit and on opposite sides of the base, 90 and a filling of porous material covering said drain tile.

In testimony whereof, I hereunto affix my signature.

CHRISTIAN GOTTWALD.
